Verlys of America, Inc., New York, N. Y., a corporation of New York

Application April 23, 1938, Serial No. 76,715

Term of patent 7 years

To all whom it may concern:

Be it known that I, Maurice Exelmans, a citizen of the Republic of France and a resident of Paris, France, have invented a new, original, and ornamental Design for an Ashtray or Similar Article, of which the following is a specification, reference being had to the accompanying drawing, forming a part thereof.

The figure is a perspective view of the ashtray,
showing my new design.

I claim:

The ornamental design for an ashtray or similar article, as shown.

MAURICE EXELMANS.
